To all whom it may concern:

Be it known that I, JOHN H. The nature of my invention consists in so arranging emblems as to show above the shelf A a five-pointed star, B, above which are balls, C, cross-cannons D D, sword E, all being surmounted by an eagle, F; below and on the right of star B are an anchor, G, a

flag, H, and cross-guns I I; below star B, and on the left are a bugle, J, flag K, and cross-sabers L L; the shelf being supported by a square and ornamental scroll-work, the parts above and below the shelf being inclosed in scroll-work, the whole making an ornamental emblematic bracket.

What I claim, and desire to secure by Letters Patent, is—
